UNITED STATES PATENT OFFICE.

MAUD M. McCULLOUGH, OF ST. LOUIS, MISSOURI.

IRONING-BOARD.

1,157,317.

Specification of Letters Patent.

Patented Oct. 19, 1915.

Application filed January 7, 1915. Serial No. 1,057.

To all whom it may concern:

Be it known that I, MAUD M. McCULLOUGH, a citizen of the United States, residing at 4722 McPherson avenue, St. Louis city, State of Missouri, have invented certain new and useful Improvements in Ironing-Boards, of which the following is a specification.

My invention relates to improvements in ironing boards, the principal object of my invention being to construct an ironing board in sections which are capable of being readily assembled or taken apart, thus providing a board which can be packed into a comparatively small space for storage or transportation; further, to provide simple and readily releasable means for securing the sections of the ironing board to each other; further to equip the ironing board with simple means for firmly securing a cover in position on the ironing board; and further to equip the ironing board with means whereby it may be readily applied to a table or the like.

With the foregoing and other objects in view, my invention consists in certain novel features of construction and arrangement of parts, hereinafter more fully described, claimed and shown in the accompanying drawings, in which—

Figure 1 is a perspective view of an ironing board of my improved construction, a portion of the cover thereof being broken away. Fig. 2 is a view looking against the bottom of my improved ironing board. Fig. 3 is an enlarged detail section taken approximately on the line 3—3 of Fig. 2. Fig. 4 is an enlarged detail section taken approximately on the line 4—4 of Fig. 2. Fig. 5 is a detail section taken approximately on the line 5—5 of Fig. 3. Fig. 6 is an enlarged detail section taken approximately on the line 6—6 of Fig. 2.

Referring by numerals to the accompanying drawings, 1 and 2 designate the two sections of the board, the same being preferably formed of wood and of any suitable size. When these two sections are properly assembled they form an elongated member 0 which gradually tapers toward one end and both ends being rounded, such being the usual shape of ironing boards.

The connecting means between the two sections comprises loop members 3 secured in any suitable manner to the underside of section 1 adjacent to the straight edge there-

of and fixed in said loop members are outwardly projecting fingers 4 which are adapted to engage in loops 4^a, which latter are fixed to the underside of section 2 adjacent to the straight edge thereof. These connections form a mortise and tenon arrangement whereby the two sections can be readily assembled or taken apart and when properly assembled, said sections are firmly secured to each other.

As a convenient means for securing the board to the corner of a table or like support a hinged bail 5 is arranged on the underside of member 1 adjacent to the rounded end thereof, and when the board is applied to the corner of a table so as to be supported thereby, the board is manipulated so that the corner of the table occupies a position between the member 1 and the bail.

Fixed to the undersides of sections 1 and 2 are blocks 6 which serve as supports for the ironing board when the same is positioned on top of a table or the like, said blocks being located adjacent to the side edges of the sections 1 and 2. Pivottally secured to the ends of these blocks are bail-shaped clamping members 7 which are adapted to swing upwardly against the inner sides of said blocks, thereby clamping portions of the edge of the ironing board cover 8. This cover is preferably constructed of suitable fabric and shaped so as to fit over the entire board and the edges of said cover are adapted to extend beneath said board a sufficient distance to be engaged and clamped between the members 7 and blocks 6. (See Fig. 6.) The ends of the cover are adapted to be clamped to the rounded ends of the sections 1 and 2 by bow-shaped clamping members 9, the same being pivotally connected to the end portions of the sections 1 and 2.

It will be understood that a suitable pad composed of one or more layers of fabric or the like may be located on top of the ironing board beneath the cover thereof, and such construction forms a smooth yielding ironing surface.

When the cover is properly applied to the ironing board and clamped in position thereupon by the members 7 and 9, it will be impossible to draw the sections of the board apart, and thus when properly set up for use, the board performs the functions of a one piece structure.

It will be understood that the blocks 6

- have greater depth than the loops 3 and 5, and thus said loops do not touch the top of the table or support when the board is properly positioned thereupon. When the 5 board is arranged for use on a flat support, the member 5 can be swung upwardly as shown by dotted lines in Fig. 3, thus occupying a position immediately adjacent to the underside of section 1.
- 10 An ironing board of my improved construction is comparatively simple, can be cheaply manufactured, can be packed into a comparatively small space for storage or transportation, can be readily assembled or 15 taken apart, and can be readily applied to the corner of a table for use.

It will be readily understood that minor changes in the size, form and construction of the various parts of my improved ironing 20 board can be made and substituted for those herein shown and described, without departing from the spirit of my invention, the scope of which is set forth in the appended claims.

25 I claim:

1. An ironing board made in sections, and a cover overlying said sections and secured

to said sections, whereby the same are held together.

2. An ironing board made in sections, bow 30 clamps hinged to the outer ends thereof, and a cover overlying said sections, the ends of which cover are adapted to be clamped between the ends of the board and said bow clamps, whereby the sections of the board 35 are held together.

3. An ironing board, and a transversely disposed bail hinged to the underside thereof of near one end, the space between which bail and ironing board is adapted to receive 40 a flat support such as the corner of a table, said bail being adapted to swing upward against the underside of said board when the latter is positioned on top of the table.

4. An ironing board made in sections, a 45 cover overlying said sections for holding the same together, and means on each section for gripping the edges of said cover to hold the same in taut condition on the assembled board.

MAUD M. McCULLOUGH.
